(57) **CLAIM**

I claim the ornamental design for a display screen or portion thereof with graphical user interface, as shown and described.

DESCRIPTION

FIGURE is the front view for a display screen or portion thereof with graphical user interface showing my new design.

The even broken line showing the graphical user interface is included for the purpose of illustrating environmental structure and portions of the article and forms no part of the claimed design.

The dot dash line showing the display screen is included for the purpose of illustrating environmental structure and portions of article and forms no part of the claimed design.
